Richard D. Owen
ATTORNEY.

UNITED STATES PATENT OFFICE.

BENJAMIN D. KILCUP, OF ASTORIA, NEW YORK.

LINE STRETCHER.

Application filed August 22, 1924. Serial No. 733,623.

To all whom it may concern:

Be it known that I, BENJAMIN D. KILCUP, a subject of the King of England, residing at Astoria, in the county of Queens and 5 State of New York, have invented certain new and useful Improvements in Line Stretchers, of which the following is a specification.

This invention relates to line stretchers 10 and more particularly to a novel and improved construction and arrangement for maintaining a clothes line taut when supporting considerable weight.

One of the objects of my invention is to 15 provide a line stretcher particularly adapted for clothes lines wherein tension may be exerted and maintained so that the line or cable will operate efficiently over the pulleys.

Another object of my invention is the 20 provision of a novel and improved stretching device including a plurality of line spacers, constructed and arranged to prevent the sagging of the top and bottom lines when supporting a considerable weight.

25 To enable others skilled in the art to fully comprehend the underlying features of my invention that they may embody the same in the various modifications in structure and relation contemplated, drawings 30 depicting a preferred form have been annexed as a part of this disclosure and in such drawings, similar reference characters denote corresponding parts throughout all the views, of which,

35 Figure 1 is a view showing my invention as applied to a conventional clothes line.

Figure 2 is an enlarged, side view of the stretcher.

Figure 3 is a plan view.

40 Figure 4 is a vertical cross sectional view taken on the line 4—4 of Figure 2.

Referring now to the drawings wherein like reference characters designate corresponding parts throughout all the views, 5 45 designates the wall of a building adjacent a window sash and 6 a clothes line support between which the clothes line is attached. The clothes line 7 passes over a pulley 8 and said clothes line is trained over a pulley 9 adjustably and rotatably mounted in a sliding frame 10. The frame and pulley is supported on a stationary frame composed of parallel, side members 11, 12, which are connected at their front and rear ends and

formed with an upper and lower guide loop 55 13, 14, through which the line passes and is guided over the pulley 9. The top edges of the side members 11, 12, are provided with notches 15 which are adapted to receive a catch or lock 16, consisting of an open loop, 60 the ends 17 of which are pivotally mounted in extension eyes 18, formed with the sliding frame 10, above referred to. The frame is provided with studs 19, 20, which engage one end of a tension spring 21, the opposite 65 end of said spring being adapted to bear against the arms of the catch and retain the same in their locked position in the notches.

A lever 23 pivotally mounted as at 24 on 70 a connecting stud 25 at the opposite ends of the members 11, 12, constituting the stationary frame, is connected by a pair of tension rods 26, the opposite ends of which are fastened to the studs 19, 20. A supporting eye 27 is provided whereby the stretcher may be attached to the wall of a building 75 as shown and above described. The stationary frame is provided with an extension 28 to which the end of a link chain 29 is 80 attached, the opposite end of the link chain being adapted to be held by one of the studs, above referred to. A plurality of line spacers 30, preferably closed loops or rings, 85 are positioned on the line 7 so that they may be moved out with said line to space the upper and lower strands as shown by Figure 1. When not in use, the line spacers are gathered and held by the link chain, 90 which passes therethrough.

From the above description, it will be seen that since the adjusting frame 10, which carries the pulley 9, may be moved by tension exerted by the tension rods and lever, 95 the line may be maintained in its proper position with respect to the pulleys at all times regardless of the weight carried thereby. When it is desired to release the tension, by raising the catch from the notches against the resistance of the spring 21, the 100 sliding and adjustable frame 10 is released.

While I have illustrated and described my invention with some degree of particularity, I realize that in practice various alterations therein may be made. I therefore 105 reserve the right and privilege of changing the form of the details of construction or otherwise altering the arrangement of the

correlated parts without departing from the spirit of the invention or the scope of the appended claims.

Having thus described my invention, what I claim as new and desire to secure by United States Letters Patent is:—

1. A line stretcher of the class described comprising a line support adapted to be attached at one end, line guiding means formed with the support at its opposite end, an adjustable frame and pulley movable with respect to the support, a lever pivoted to said support and tension rods attached to
- 10

the frame and means for locking the said frame in its adjusted position.

2. A line stretcher of the class described comprising a line support having line guiding loops, a slid able frame carrying a pulley over which the line is guided and movable with respect to the support, a lever pivoted to the support, tension rods connecting the lever and movable frame and resilient locking means for retaining the frame in its adjusted position.

In testimony whereof I affix my signature.
BENJAMIN D. KILCUP. [L. s.]
